DRIP TRAY

William W. Woodward, Baltimore, Ohio, assignor
to The Fairfield Paper and Container Com-
pany, Baltimore, Ohio, a corporation of Ohio

Application August 23, 1949, Serial No. 111,941

5 Claims. (Cl. 229—23)

1

My invention relates to a drip tray. It has to do, more particularly, with a shallow tray made from paperboard or corrugated board which is particularly suitable for use under a car in a garage so that any oil dripping therefrom will be received and retained by the tray.

As is well known, a small amount of oil will drip from the crank case of a car and if some means is not provided for collecting it, will produce an unsightly pool on the floor which will also be a safety hazard. It has been common to provide metal trays for collecting the oil drip. However, these trays are quite expensive and they become unsightly and must be cleaned from time to time.

It is the object of my invention to provide a drip tray formed of paperboard, corrugated board or similar board, which will effectively collect the oil drip but which is inexpensive and can, therefore, be discarded whenever it becomes unsightly or saturated with oil.

Still another object of my invention is to provide a drip tray of paperboard which is normally in knock-down or flat condition so that shipping thereof in large groups is facilitated.

A further object of my invention is to provide a tray formed of paperboard or the like which can be set up easily without the use of staples or similar fastening devices.

An additional object of my invention is to provide a tray of the type indicated which is provided with members which lock the end walls and side walls in upright position when the tray is set up, such members being also formed of the same material as the body of the tray.

A further object of my invention is to provide a tray wherein the locking members also serve to reinforce the tray to provide a relatively rigid structure.

Still another object of my invention is to provide locking members of the type indicated above which not only serve the locking function but which are so shaped and arranged when the tray is set up that such members can bear advertising data or other indicia.

Another object of my invention is to provide locking members which are in flat condition before the tray is set up and can, therefore, have the advertising data printed thereon by usual simple printing processes.

Various other objects will be apparent.

The preferred embodiment of my invention is illustrated in the accompanying drawing wherein in similar characters of reference designate corresponding parts and wherein:

2

Figure 1 is a perspective view of a tray made according to my invention showing it after it has been set up.

Figure 2 is a detail in perspective illustrating a corner of the tray as the adjacent side wall and end wall are being brought together.

Figure 3 is a perspective view illustrating how a locking member is used to lock the side wall and end wall together.

Figure 4 is a plan view of the main blank used in forming the body of the tray.

Figure 5 is a plan view of a blank of the type used in forming the end locking members.

With reference to the drawing, in Figure 4, I have illustrated a blank 6 which is scored and slit in the proper manner to form the body 6a (Figure 1) of the tray. This blank is a flat sheet of paperboard or the like of rectangular form. The blank is provided with the side score lines 7, the end score lines 8, and with slots 9 at each end of each score line 8 and in alignment therewith. Slots 9 extend inwardly to score lines 7. This slotting and scoring produces the side walls 10 and the end walls 11. In each end of each end wall 11, a slot 12 is provided in alignment with the score line 7. The slots 12 do not extend the full depth of the end walls 11. An additional slot 13 is provided in each end of each end wall 11, the slot 13 being of the same depth as slot 12 and being parallel therewith. Another slot 14, identical with slot 13, is formed in each end of each side wall 10 and is spaced from the adjacent slot 9 being parallel therewith. The slot 14 is spaced from the end of the side wall 10 or slot 9 a distance equal to the distance between the slot 13 and the adjacent end of the end wall 11. When blank 6 is folded along score lines 7 and 11, the walls 10 and 11 will be upstanding from the flat bottom.

For cooperating with the blank of Figure 4, I provide a pair of end locking members 15a. Each of these members is formed from a blank 15 of the type shown in Figure 5. This blank comprises a flat elongated rectangular sheet of paperboard or the like which is provided with a pair of score lines 16 running the entire length thereof being parallel with each other and being spaced apart a distance equal to the spacing of the slots 12 and 13 of blank 6. At the ends of the blank 15, the opposed slots 17 and 18 are formed in the side edges and are extended inwardly towards each other. These slots are of the same depth as the slots 12, 13 and 14 of the main blank 6 and are adapted to cooperate therewith, as will later appear. The slots 17 and 18

are in alignment with each other and are spaced from the end of the blank 15 being parallel therewith. The distance between the two slots 17 and the two slots 18 corresponds to the distance between score lines 7 of blank 6 or in other words, the distance between side walls 10. When the blank 15 is folded along the score lines 16, it will include the top wall 19 and the depending vertical walls 20.

To set up the tray, the blank 6 is folded along the score lines 7 and 8 to produce the upstanding side walls 10 and end walls 11. Each end of each end wall 11 is bent along the slot 12 to form an inwardly extending locking tab 21, as shown in Figure 2. The tab 21 is slipped inside the side wall 10 and the slot 13 therein will align with the slot 14 in the side wall when the side wall and end wall are brought into complete vertical position. To lock the side and end walls in vertical position, the locking member 15a is positioned thereon. The blank 15 is folded along the score lines 16, as previously indicated. The member 15a is positioned just inside end wall 11 and then each end of the locking member is slipped into position over the adjacent side wall 10 and the tab 21 which are in face contact, as shown in Figure 3. The inner vertical wall 20 of the locking member 15a will slip down into the aligning slots 13 and 14 and the locking slot 17 will interlock with the uncut portions of tab 21 and wall 10 at the lower end of slots 13 and 14, while the aligning slots 13 and 14 will interlock with the uncut upper portion of wall 20 at the upper end of slot 17. Similarly, the outer wall 20 of the locking member 15a will slip down into the slot 12 with such slot interlocking with the uncut joint between tab 21 and wall 11 at the bottom of slot 12, while the slot 12 will interlock with the upper uncut portion of wall 20 at the upper end of slot 18. Thus, an interlocking structure is provided which joins the end walls and side walls together. The members 15a not only serve as locking members but also as reinforcing members to give rigidity to the ends of the tray. It will be noted that the ends of members 15a project slightly beyond the side walls 10.

The blank 15 may be printed with any suitable advertising or other indicia while it is in flat condition. For example, such indicia may be on the inside vertical wall 20, as illustrated in Figure 1, and may be of luminous ink so as to show up at night when a car's lights are cast on it.

The drip tray of this invention is extremely simple and inexpensive. Because of its low cost, it can be discarded whenever it becomes soaked with oil or unsightly. It may be disposed of by burning. Shipping of the tray in large numbers is facilitated because it is originally in knock-down condition. However, it can be set up with ease.

Although I have described this tray as being useful as a drip tray, it should be understood that it could be used for other purposes. For example, it could be placed on the seat of a car when a mechanic is working thereon so that

he can put greasy tools or rags thereon. Other uses are possible.

Having thus described my invention, what I claim is:

5 1. A drip tray or the like formed from paper-board or similar material comprising a flat bottom having upstanding peripheral walls disposed in angular relationship, adjacent walls being provided with overlapping portions at their corners, and a separate locking member extending along one of the adjacent walls, said locking member having a portion at each end which interlocks with the overlapping corner portions of two adjacent walls to connect them together and hold them in upstanding position.

10 2. A drip tray or the like formed from paper-board or similar material comprising a flat bottom having upstanding peripheral walls, and locking member extending along two opposed walls of the tray, said locking members being formed of paperboard or similar material and each having an upper wall and depending walls, the adjacent peripheral walls at each corner of the tray including a tab on one wall which overlaps the other wall, said tab and peripheral wall and the depending walls of the locking member having interlocking slots formed therein.

15 3. A drip tray or the like formed from paper-board or similar material comprising a flat bottom having upstanding side and end walls, and locking members formed from paperboard or similar material disposed at the ends of the tray and extending transversely thereof along the end walls of the tray, said locking members having portions at their ends which interlock with the side and end walls to connect them together and hold them in upstanding position.

20 4. A tray according to claim 3 wherein the end walls have locking tabs thereon which overlap the side walls, said locking members having an upper wall and a pair of depending parallel walls, said tabs and adjacent side walls having slots formed therein which interlock with slots formed in the depending walls of said locking members.

25 5. A tray according to claim 4 wherein the locking tabs and adjacent side walls each have a pair of upwardly opening slots aligning with each other, said slots being spaced apart a distance equal to the width of the top wall of the locking member, and wherein the ends of the locking members have downwardly opening slots in the side walls thereof which interlock with the slots in said tabs and side walls.

30 55 WILLIAM W. WOODWARD.
